Primary Examiner — Austin Murphy(74) *Attorney, Agent, or Firm* — Creativenture Law, LLC; Dennis J M Donahue, III; Kevin Staed(57) **CLAIM**

The ornamental design for a splashguard, as shown and described.

DESCRIPTION

FIG. 1 is an upper front perspective view of a splashguard according to a first embodiment of the design; FIG. 2 is a lower back perspective view of the splashguard shown in FIG. 1;

FIG. 3 is a front view thereof;

FIG. 4 is a back view thereof;

FIG. 5 is a top view thereof;

FIG. 6 is a bottom view thereof; and,

FIG. 7 is right side elevation view thereof.

The left side elevation view of the splashguard is a mirror image of the right side elevation view shown in FIG. 7.

The broken lines shown in the figures are for the purpose of illustrating portions of the splashguard and form no part of the claimed design.
